GEORGE L. SCHOFIELD, OF KANSAS CITY, MISSOURI.

ROTARY VALVE FOR EXPLOSIVE-ENGINE

1,190,595.

Specification of Letters Patent. Patented July 11, 1916.

Application filed November 16, 1914. Serial No. 872,389.

To all whom it may concern:

Be it known that I, GEORGE L. SCHOFIELD, a citizen of the United States, residing at Kansas City, in the county of Jackson and State of Missouri, have invented certain new and useful Improvements in Rotary Valves for Explosive-Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a rotary valve for explosive engines, and has for its principal object to provide a rotary valve wherein the impact occasioned by explosion of gas within an engine cylinder, is balanced to obviate uneven pressure and strain on the valve and its inclosing parts. In accomplishing this object I have provided the improved details of structure, the preferred embodiment of which is illustrated in the accompanying drawings, wherein:

Figure I is a perspective view of an exemplification of an explosive engine in which my improved valve may be used. Fig. II is a longitudinal vertical section of the same. Fig. III is a transverse vertical section on the line III-III of Fig. II. Fig. IV is a detail perspective view of the rotary valve. Fig. V is a perspective view of a retaining collar in the delivery end of the valve housing. Fig. VI is a detail perspective view of the valve balancing cup or thimble.

Referring more in detail to the parts:— 1 designates an explosive engine of an ordinary vertical type and is here shown merely to facilitate the illustration of my improvements, and with the understanding that the valve may be combined in a horizontal engine, vertical engine, or other types of explosive engines.

The engine 1 comprises a cylinder 2, wherein charges of fuel are exploded, and a valve housing 3 comprising mechanism for controlling the passage of fuel to the cylinder, the compression and ignition of the charge and exhaustion of the burnt or spent gases at proper intervals.

The specific construction of the housing 3 comprises interior chambers 5 and 6 of

different diameter, the large chamber being 55 at the outer end of the housing and having an annular seat 7 on account of the difference in diameter between the two chambers. Revolubly mounted within the smaller chamber 5 is a rotary valve 9, having a port 60 11 therein adapted for independent communication with the intake and exhaust ports 12-13, that extend through the housing 3 to the chamber 5 from the respective intake and exhaust conduits 14-15 that are fed 65 from a suitable carbureter and may deliver through a suitable muffler, not shown. The valve 9 has an integral end 17 that closes its outer end and forms a cup-shaped structure that fits snugly within the chamber 5 70 to obviate the escape of gas or vapor between the rotating or valve ring and the inner surface of the housing and obviating the necessity of stuffing boxes or packing rings.

Seated within the valve 9 is a cup 10 having intake and exhaust ports 20-21 adapted for communication with the intake and exhaust ports 12-13 in the valve housing through the valve port 11, when the latter 80 is brought to proper position, and having a balance port 22 opposite the intake and exhaust ports; it being apparent that as the intake and exhaust ports are located adjacent each other, the single balancing port 85 may be located diametrically opposite a point midway between the intake and exhaust ports, so that expansion of gases within the cylinder and explosion chamber may not cause unequal pressure or strain on the rotating valve; the cup 10 also protecting the rotating valve 9 from carbon and heat of the explosion. The open end of the cup 10 has a flared mouth 24 overlying the beveled outer end 25 of the valve ring 9 and is provided with a flange 26 which overlies the seat 7 in the valve housing and is preferably separated therefrom by a packing ring 26 to better insure against the leakage of gas through the joint.

The cup 10 is held in place by a retaining collar 28, which is preferably formed integral with a cap 29 that may be attached to the housing by bolts 30 and seals the valve chamber, the sleeve being provided with 105 sockets 31 for receiving the ends of dowel pins 32 that project from the ring flange 26. The sleeve 28 is provided with a port 33

through which the charges of fuel vapor may be delivered from the outer valve chamber into the interior of the cylinder 2.

A spark plug 34 is preferably arranged 5 diametrically opposite the intake and exhaust ports and in alinement with the balance port 22 in the valve cup, so that when the spark is energized to ignite the charge of fuel, it is exposed to the interior of the 10 valve chamber, but is covered by the rotary valve immediately following the ignition, thereby protecting the plug from the oil and heat and thereby preventing the accumulation of carbon on the plug.

15 In order to rotate the valve 9 in proper synchronism with the sparking mechanism, I provide a shaft 35, which is revolutely mounted in a bearing boss 36 on the end of the housing and is fixed at its inner end in 20 the cap 17 of the valve ring 9; the outer end of the shaft being provided with a drive wheel 37 whereby the shaft may be driven from suitable mechanism that may be driven from the crank shaft of the engine that is 25 served by the valve.

In assembling the parts, the rotary valve may be first installed by removing the drive wheel and forcing the valve into the inner chamber of the housing, so that the shaft 30 35 projects through its bearing. With the valve in place the cup is dropped into the valve chamber with its annular flange resting on the packing ring, and the cap, with its collar next installed, so that the dowel pins on the valve cup project into the sockets in the inner end of the collar. With the parts so arranged and operatively connected with the engine driving mechanism, the 35 valve cup is held against rotation, while rotation of the shaft 35 will rotate the valve ring, so that communication is established at proper intervals between the intake and exhaust ports; the operation in this respect being that of any ordinary explosive engine, 40 except as to the method of securing the communications by the rotary member instead of the usual puppet valves.

With a construction of this character, were the cup 10 closed except for the intake and exhaust ports, when a charge 45 would be exploded in the cylinder the explosion of each charge would exert a pressure through the cup ports against the rotary valve ring, which would tend to drive the 50 ring outwardly and thereby exert a retarding contact of the ring on the inner face of the housing, and as the presence of the intake and exhaust ports in alinement with the like ports in the valve cup would afford 55 no backing for the rotary ring at such points, there would be a tendency to force the ring to wear out of shape, particularly after repeated explosions. In order, however, to balance the pressure on the valve 60 ring, I have provided the balance port in

the valve cup, so that when each charge is exploded the pressure in the cup is relieved equally, or substantially so, on opposite sides of the rotary ring and such uneven retarding pressure is eliminated.

Having thus described my invention, what I claim as new therein, and desire to secure by Letters-Patent, is:

1. A rotary valve comprising a housing having inner and outer valve chambers and provided with intake and exhaust ports and with a spark plug, a rotary sleeve mounted in one of the chambers, and having a port adapted for communication with either of the housing ports and for exposing said plug to the interior of the chamber, a valve cup located within the sleeve and having intake and exhaust ports adapted for communication with the housing ports, and having an opposite balance port in alinement with the valve port, a sleeve in the other valve chamber having pin and dowel connection with the valve cup, means for holding the sleeve against rotation, means for closing the outer end of the second chamber and holding the collar in place, and means for rotating said sleeve.

2. A rotary valve comprising a housing having a valve chamber and intake and exhaust ports opening to said chamber, a spark plug exposed to the interior of said chamber, a cup in the chamber spaced from the housing, the said cup having intake and exhaust ports adapted for communication with the intake and exhaust ports in the housing and having a port through which a spark from said plug may be projected to the interior of the cup and a valve member rotatably mounted between the cup and housing and having a port adapted for passing the intake and exhaust ports and the spark plug in proper sequence.

3. A rotary valve comprising a shouldered valve chamber and having intake and exhaust ports opening to said chamber, a cup located in said valve chamber and an end flange seated against the shoulder thereof, the said cup having separate intake, exhaust and spark ports, and a valve member rotatably mounted between the cup and housing and having a single port adapted for exposing the housing intake and exhaust ports and the spark plug to the proper cup ports in determined sequence.

4. A rotary valve comprising a housing having an interior chamber closed at one end and having a shoulder at its opposite end, the said housing having separate intake and exhaust ports and having a spark plug exposed to its interior, a cup mounted in and spaced from the inner face of said housing, said cup being closed at the closed end of the housing and having a flaring mouth at its opposite end, a shoulder on the open end of said cup seated in the housing shoulder, the

said cup having intake, exhaust and spark ports in radial alinement with the housing intake and exhaust ports and with the spark plug, a valve member rotatably mounted between the cup and housing and having a closed end located between the closed end of the housing and the closed end of the cup, and having a port adapted for exposing the cup ports in proper sequence and a shaft ro-

tatably mounted in the closed end of the housing and fixed to the valve member.

In testimony whereof I affix my signature in presence of two witnesses.

GEORGE L. SCHOFIELD.
